FLUID-PRESSURE-RESPONSIVE CONTROL
CIRCUIT FOR DIE-CASTING PRESSES

Walter Ernst and Philip J. Lindner, Mount Gilead,
Ohio, assignors to H-P-M Development Cor-
poration, Wilmington, Del., a corporation of
Delaware

Application September 28, 1944, Serial No. 556,205

7 Claims. (Cl. 60—52)

1

This invention relates to fluid operable apparatus and, in particular, to fluid operable devices wherein relatively high speeds are desired.

There are many instances in the field of application of fluid actuated devices wherein high speed operation is necessary or desirable in order better to accomplish the work to be done, or in order to reduce the time required for the accomplishment thereof. Particular cases in which high speed operation is essential include, die casting, forging, molding and other similar work operations. Most particularly in the die casting of such metals as magnesium and its various alloys, it is necessary to drive the molten casting metal into the die cavity at great speeds in order to produce castings of good and uniform quality.

Heretofore it has been customary to obtain high speed of operation through the use of large capacity fluid sources, or to sacrifice power for speed by reducing the size of the driven element or elements.

It has been found, however, that certain jobs such as the die casting of magnesium and its alloys require speeds in excess of those readily obtainable with this type of apparatus.

Accordingly, it is an object of the present invention to provide a fluid operable device, including a fluid source or sources therefor such that high speed operation is obtainable without any substantial reduction in available power.

Also, in the die casting of metals it is necessary, because of the high temperatures thereof, to handle the molten metal with care in order to prevent harmful and possibly serious injury to the machine operator.

Accordingly, it is another object of the present invention to provide an operating system for a fluid operable die casting machine including automatic controls for insuring that the molten metal is completely enclosed within the machine before the latter is set into full speed operation.

It is another object to provide in a die casting machine having a high speed injection ram an operating system for the same ram such that the initial portion of the working stroke thereof is accomplished at relatively low speeds.

These and other objects and advantages will become more clearly apparent upon reference to

2

the following description taken in connection with the accompanying drawings, in which:

Figure 1 is a vertical longitudinal section through a fluid operable device constructed according to this invention;

Figure 2 is a diagrammatic view of the control system which forms a part of this invention; and

Figure 3 is a diagrammatic view showing the wiring diagram for use in connection with the 10 control system of Figure 2.

General arrangement

This invention comprises, generally, a fluid operable motor to which pressure fluid is supplied from two separate fluid sources. The motor, while it may be of any suitable type, is here shown as a reciprocating type plunger motor having a differential piston attached thereto and reciprocably mounted in a pressure cylinder.

20 A source of pressure fluid, substantially unlimited in comparison with the capacity of the motor is adapted to supply actuating fluid to one area of the differential piston, preferably to the advancing area. This source of fluid pressure 25 comprises a compressible or condensable medium which may be continuously in communication with the area to which it supplies actuating fluid. Any suitable compressible fluid medium may be used in this connection, such as nitrogen, 30 hydrogen or similar gases or mixtures thereof which have suitable characteristics.

Retracting means, which may be fluid operable and may comprise a second source of pressure fluid is adapted selectively to drive the motor opposite to the direction to which it is driven by the 35 said first fluid source. The second fluid source, according to this invention, may comprise an incompressible fluid medium and a pressure generator therefor. The delivery of fluid from the second fluid source to the plunger retracting 40 means is preferably controlled by a distributing valve which is also operable to exhaust the said retracting means in order to accomplish the advancing movement of said plunger.

45 The aforementioned valve means has, in operative association therewith, means for regulating the rate of exhaust of the retracting means during the initial part of the advancing stroke so that the speed of movement of the plunger is thereby retarded. When the plunger has moved a pre-

determined distance suitable control means such as a limit switch is engaged by the said plunger and the retarding means is thus, automatically, rendered ineffective and the plunger commences the high speed portion of its advancing stroke.

The means associated with the valve for controlling its operation is preferably a fluid operable pilot system which has choke valves suitable arranged therein so that the speed of movement of the valve member is controlled.

Structural arrangement

Referring to the drawings, and particularly Figure 1, the device illustrated therein comprises a reciprocating fluid motor having a cylinder 1 and a piston 2 reciprocably mounted therein, the latter having a plunger 3 attached thereto. The plunger 3 has an enlarged portion adjacent the piston 2 at 4 which is adapted to be received by the tapered recessed portion at 5 in the end wall 6 of the cylinder 1.

The plunger 3 has attached to the free end thereof a coupling 7 to which, in turn, is attached a second plunger or work ram 8. Also attached to the ram 8 adjacent the coupling 7 is a cam member 9 adapted, when the ram has moved a predetermined distance, to engage the roller 10 of the limit switch 11 thereby to actuate the latter.

The plunger 8 reciprocates within a cylinder 12 which is suitably attached to, or is integral with, a bolster 13. An aperture at 14 is provided in the cylinder 12 for the purpose of permitting the introduction therein of the plastic material to be molded in the die or mold generally indicated by the dashed outline at 15.

The right end of the cylinder 1 terminates in a block having a central longitudinal bore 16 therein. Attached to the block is a source of pressure fluid of large capacity relative to the size of the motor. This source may comprise a cylinder or tank 17 within which is contained a compressible fluid medium such as nitrogen, hydrogen or similar gases or mixtures thereof. A passage 18 communicates from the interior of the tank 17 to the bore 16 and permits passage of fluid from the tank to the larger area of the piston 2. A shut-off valve or similar flow controlling means may be provided in the passage 18, 16 as, for instance, the needle valve indicated at 19. The valve 19 is not only useful to control the rate of fluid flow to and from the cylinder 1 but likewise may be used to close off fluid communication between the tank 17 and the cylinder 1 thereby to prevent wasteful leakage of the fluid medium from the tank 17 when the device is idle. In operation the valve is preferably opened wide.

Referring to the piston 2, this member comprises a shouldered cylindrical member having packing or other suitable sealing means mounted around the periphery thereof in order to inhibit leakage from one side of the said piston to the other. The left end of the cylinder 1 is connected by means of a conduit 20 with a valve 21 which is also adapted, by means of a conduit 22, to communicate with the reservoir 27 and, by means of a conduit 23, with a pump or pressure generator 24. Also connected with the valve is a conduit 25 which connects with the pump control cylinder 26. The valve 21 is preferably located adjacent the cylinder 1 and within the reservoir 27 so that the fluid flow from the cylinder through the valve and into the reservoir is relatively free and unrestricted.

The valve 21 includes a reciprocable valve mem-

ber 28 which is adapted to be moved into a first end position to interconnect the conduits 20 and 23 and, into a second end position to interconnect the conduits 23 and 25 and the conduits 20 and 22. The valve member 28 has the reduced diameter projections 29 and 30 on either end thereof and the fluid operable pistons 31 and 32 reciprocably mounted over the projections 29 and 30 respectively. The pistons 31 and 32 are reciprocable within the cylinders 33 and 34, respectively, and are adapted to engage the valve member and move the same to a center position where fluid communication between the conduits connected therewith is interrupted.

Actuating fluid is conducted to the cylinders 33 and 34 by the conduits 35 and 36, respectively, which lead to the pilot valve 37. Also connected with the valve 37 is a conduit 38 which conducts fluid from the conduit 23 to the said valve, and the exhaust conduit 39. The valve 37 comprises a valve member 40 movable into a first end position to interconnect the conduits 38 and 36 while connecting the conduit 35 to exhaust and, into a second end position for connecting the conduit 38 with the conduit 35 while simultaneously connecting the conduit 36 to exhaust. The valve member 40 is also movable into an intermediate position where the conduit 38 is connected with both conduits 35 and 36. In this latter position the valve member 28 of the valve 21 is moved to its center or neutral position.

The conduits 35 and 36 have therein the choke valves 41 and 42, respectively, which serve to regulate the flow of pilot fluid to the valve 21 so that the reciprocation of the valve member 28 is accomplished without shock.

The conduit 36 also comprises the choke valve 43 and the check valve 44. The check valve 44 permits the free flow of pilot fluid from the valve 37 to the cylinder 34 while the choke valve 43 is adapted to throttle the discharge from the cylinder 34 for a purpose which will become more apparent hereinafter. Connected with the conduit 36 between the choke valve 43 and the cylinder 34 is a conduit 45 which leads to exhaust and includes a two way valve 46. The two way valve 46 has a reciprocable valve member therein which is normally urged into position to interrupt the flow of fluid through the conduit 45 by a spring 47 and is moved into position to permit the flow of fluid through the said conduit by the solenoid S1.

The valve member 40 of the valve 37 is urged into one of its end positions by the spring 48 and into its other end position by the solenoid S2. The hand lever 49 is provided for the purpose of positioning the valve member manually if it be desired to inch the plunger 3 forward.

The movable portion of the mold 15 is attached to a platen 50 which is actuated by a motor means 51 which is preferably fluid operable. The motor means 51 is supplied with actuating fluid by the conduits 52 and 53 which lead to a distributing valve 54 which receives pressure fluid from the pump 55 through a conduit 56. The pump 55 draws fluid from the reservoir 27 through the conduit 57 which connects with the main exhaust line 58.

The valve 54 is urged into one position by the spring 59 and into its other position by a solenoid S3.

There may be provided, if desired, the check valve 59' in the conduit 56 and the check valve 60 in the conduit 23. Likewise, if desired, the

pumps 55 and 24 may be bypassed by the relief valves 61 and 62, respectively.

Returning to the valve 21, the valve member 28 is adapted to abut stops at either end of the valve which may comprise the screw threaded members 63 and 64. The adjustable stops 63 and 64 are provided for the purpose of limiting the movement of the valve member 28 thereby to control the rate of fluid flow through the valve 21 should it be desirable to do so. Arranged between the stop member 64 and the portion 30 of the valve member 28 is a plunger 65, the right end of which is hydraulically connected by the conduit 68 with the passage 16 in the cylinder 1. The purpose of the plunger 65 is to provide for the reversing of the plunger 3 should the pilot fluid from the valve 37 be cut off for any reason.

Referring to Figure 3, there is shown the electrical circuit which actuates the various solenoids. The circuit in Figure 3 comprises the power lines L1 and L2 between which are arranged the solenoids S1 and S2 and the contactors A and B. The contactor A is connected from the line L2 through a pair of normally closed blades B1 through a stop switch 70 and a start switch 71 with the line L1, the switch 71 being by-passed by a hold-in circuit provided by the normally open contactor blades A1. The solenoid S2 is connected between the lines L1 and L2 through the normally open contactor blades A2 and the solenoid S1 is connected between the lines L1 and L2 through the normally open contactor blades A3 and the limit switch 11. The contactor B, which actuates the blades B1, is connected between the lines L1 and L2 through the time-control switch 72 which may comprise a time delay element or suitable means for synchronizing the actuation of B with the actuation of the mold clamping motor 51.

Operation

Assuming that the device is in the position shown in Figures 1 and 2, an advancing stroke, that is, movement to the left of the plungers 3 and 8, is accomplished by energizing the solenoid S2 so as to shift the valve member 40 of the valve 37 downwardly thereby directing pilot fluid from the discharge side of the pump 24 through the conduits 38 and 35 into the cylinder 33. The energization of the solenoid S2 is accomplished by closing the start button 71 whereupon the contactor A is energized and closes the blades A1 and A2. The blades A1 serve to maintain the contactor A energized while the blades A2 affect the energization of the solenoid S2. As previously mentioned, the control 72 may comprise means whereby the blades B1 are held open until the mold halves are suitably clamped together thus providing a safety feature.

When the pilot fluid is introduced into the cylinder 33 it acts upon the piston 31 and the rod 29 to move the valve member 28 to the right. As the valve member 28 moves to the right fluid is expelled from the cylinder 34 and passes through the conduit 36 and the valves 42 and 43 to the valve 37 whence it is exhausted through the conduit 39 to the exhaust conduit 58. The valve 43 is adjusted so that the movement of the valve member 28 is relatively slow thus throttling the exhaust connection established between the conduits 20 and 22. The valve 43 is so adjusted that the throttling effect is continued until the cam 9 engages the roller 10 of the limit switch 11. At this time the end of the plunger

8 has completely covered the aperture 14 thereby trapping the molten metal within the cylinder 12.

When the limit switch 11 is closed the solenoid S1 is energized and shifts the valve 46 into position to connect the conduit 45 with the exhaust conduit 58. The exhaust of fluid from the cylinder 34 is now relatively free and unrestricted and the valve member 28 moves rightwardly at greater speed and the restriction between the conduit 20 and 22 is substantially eliminated. The plunger 3 now commences the high speed portion of its stroke and moves leftwardly to drive the molten metal into the dies 15.

Following the accomplishment of the molding or casting process, the contactor A may be de-energized manually or by suitable automatic means contained within the time-control switch 72. The deenergization of A deenergizes S2 so that the spring 48 restores the valve member 40 to its Figure 2 position. The valve member 28 is thus also restored to its Figure 2 position and the plungers 3 and 8 move to their retracted position.

The movement of the motor 51 may be controlled by the energization and deenergization of the solenoid S3 by the switch 73 in series therewith.

During the advancing stroke of the plungers 3 and 8 the discharge line 23 of the pump 24 is connected with the conduit 25 which conducts pump pressure to the control cylinder 26 thereby substantially unloading the pump during the said advancing stroke.

It will be apparent that this invention provides for a high speed fluid operable die casting machine in which the injection ram or plunger moves at a reduced rate of speed until the filling opening is covered thereby preventing any of the molten metal from being splashed out of the injection cylinder.

It will be apparent that various modifications may be made in the structure and arrangement of this device without in any way departing from the spirit of the invention.

Having thus fully described our invention, what we claim as new and desire to secure by Letters Patent is:

1. A fluid operable system for actuating a reciprocable plunger having an advancing and a retracting area comprising a first fluid source including an expandable fluid medium directly and continuously connected with said advancing area, a second fluid source, valve means connected with said second source and said retracting area and including a movable valve member operable to connect said retracting area with said second source or with exhaust fluid operable means associated with said valve for moving the same from one position to the other, means for supplying actuating fluid to said fluid operable means, means for restricting the exhaust from said fluid operable means as said valve is being moved into position to exhaust said retracting area thereby to retard the advancing movement of said plunger, and means including a cam and limit switch adapted in response to a predetermined advancing movement of said plunger to render ineffective said restricting means thereby to permit said valve to be moved freely to exhaust said retracting area thus permitting a rapid advancing movement of said plunger.

2. In combination with a reciprocable plunger having an advancing area and a retracting area, a first source of fluid pressure continuously connected with said advancing area, a second source of fluid pressure, a reciprocable valve member

movable to connect said retracting area with said second source or with exhaust, and means for controlling the reciprocation of said valve member comprising opposed fluid operable plungers associated with said valve member, abutment means for limiting the movement of said valve member in either direction, pilot valve means connected with said fluid operable plungers movable to direct pressure fluid to either plunger while exhausting the other to move said valve member in either direction, said pilot valve also being movable to direct pressure fluid to both of said fluid operable plungers to center said valve member, a choke valve between said pilot valve and one of said fluid operable plungers operable to retard the movement of said valve member when the same is being moved into position to exhaust said retracting area, other valve means for by-passing said choke valve, and means including a cam and limit switch adapted in response to a predetermined advancing movement of said plunger to actuate said other valve means thereby permitting the free exhaust of the fluid operable plunger associated with said choke valve so that said valve member may be moved into position freely to exhaust said retraction area.

3. In a fluid operable system, a reciprocable plunger having fluid operable advancing and retracting areas associated therewith, a first fluid source continuously connected with said advancing area, a fluid source of variable delivery, fluid pressure responsive control means associated with said second source and operable in response to a predetermined pressure to urge the same toward no delivery position, valve means movable into a first position to interconnect said variable delivery source with said retracting means while simultaneously connecting said fluid operable control means to exhaust and into a second position to interconnect said fluid operable control means with said variable delivery source while simultaneously connecting said retracting means to exhaust, fluid operable means associated with said valve and selectively operable to move the same into said first position or into said second position, and other fluid operable means associated with said valve and hydraulically connected with said first source of fluid and operable continuously to urge said valve toward said second position.

4. In a fluid operable system, a reciprocable plunger having advancing and retracting areas, a first fluid source comprising an expansible fluid medium continuously connected with said advancing area and operable to drive said plunger at high speed, a second fluid source, a valve member movable to connect said retracting area with said second source or with exhaust, a first fluid operable plunger associated with said valve member operable to move the same into position to connect said retracting area with said second source, a second fluid operable plunger associated with said valve member and operable to move the same into position to connect said retracting area with exhaust, means selectively operable for supplying actuating fluid to said first fluid operable plunger or to said second, means to control at least the first portion of the movement of said valve member when actuated by said second fluid operable plunger, and a third fluid operable plunger associated with said valve member and continuously hydraulically connected with said first fluid source and operable to move said valve member into position to connect said retracting area

with said second source substantially instantaneously upon the loss of pressure fluid for actuating at least said second fluid operable plunger.

5. A fluid operable system for actuating a plunger having an advancing and retracting area and also having means continuously biasing the plunger in its advancing direction and operable when said retracting area is exhausted to drive said plunger at high speed, a source of fluid pressure, a valve member movable to connect said retracting area with said source or with exhaust, actuating means for moving said valve member into position to connect said source with said plunger, fluid operable means for actuating said valve member into position to exhaust said plunger, means for restricting the discharge of fluid from said fluid operable means as said valve is being moved by actuating means to initiate the advancing movement of said plunger at reduced speed, and means operable automatically in response to a predetermined advancing movement of said plunger to render said restricting means ineffective thereby to permit said valve member to be moved into position to exhaust said retracting area freely thus permitting the said advancing movement of said plunger to continue at high speed.

6. In a fluid operable system for actuating a plunger having an advancing and retracting area and also having means continuously biasing the plunger in its advancing direction and operable when said retracting area is exhausted to drive said plunger at high speed, a source of fluid pressure, a valve member movable to connect said retracting area with said source or with exhaust, actuating means for moving said valve member into position to connect said retracting means with exhaust, fluid operable means for actuating said valve member into position to connect said retracting means with said source, means for restricting the discharge of fluid from said fluid operable means as said valve is being moved by actuating means to initiate the advancing movement of said plunger at reduced speed, means operable automatically in response to a predetermined advancing movement of said plunger to render said restricting means ineffective thereby to permit said valve member to be moved into position to exhaust said retracting area freely thus permitting the said advancing movement of said plunger to continue at high speed, and means of cushioning the final portion of the advancing stroke of said plunger to prevent the same from striking the end of its cylinder at high speed.

7. In combination with a reciprocable plunger having a retracting area and which is continuously biased in its advancing direction by a means operable to drive the said plunger at a high rate of speed, a source of fluid pressure, a valve member movable to connect said retracting area with said source or to exhaust, opposed fluid operable plungers associated with said valve member, means of directing pilot fluid to one or the other of said plungers for shifting said valve member to bring about the reciprocation of said plunger, flow restricting means restricting the discharge of fluid from one of said fluid operable plungers during the time said member is being moved toward position to exhaust said retracting area, electrically operated valve means for bypassing said flow restricting means and operable automatically in response to a predetermined advancing movement of said plunger, means permitting the free flow of fluid toward said plunger around said flow restricting means; and means

continuously acting on one of said plungers to move said valve member into position to connect said retracting area with said source to prevent the accidental advancing movement of said plunger upon loss of actuating pressure for said fluid operable plungers.
